UNITED STATES PATENT OFFICE.

CHARLES H. TRASK, OF LYNN, MASSACHUSETTS, ASSIGNOR TO THE DUPLEX SHOE TRIMMER COMPANY, OF PORTLAND, MAINE.

BOOT OR SHOE SOLE TRIMMING MACHINE.

SPECIFICATION forming part of Letters Patent No. 380,609, dated April 3, 1888.

Application filed June 8, 1887. Serial No. 240,597. (No model.)

To all whom it may concern:

Be it known that I, CHARLES H. TRASK, of Lynn, in the county of Essex and State of Massachusetts, a citizen of the United States, have invented a new and useful Improvement 5 in Boot or Shoe Sole Trimming Machines, of which the following is a full, clear, and exact description, reference being had to the accompanying drawings, forming a part of this specification, in explaining its nature.

The invention relates especially to a sole-edge-trimming machine having a rest for the edge of the sole especially adapted for use in trimming the heel-edge of spring-heels. It is 15 represented as organized in a duplex sole-edge-trimming machine, although it may of course be used in a machine having only a single sole-edge trimmer.

The invention further relates to various features of construction and organization, all of which will be hereinafter described.

In the drawings, Figure 1 is a view in end elevation of the head of a duplex machine having the features of my invention. Fig. 2 25 is a view in plan thereof. Fig. 3 is a view of the front, to the left of the end shown in Fig. 1. Fig. 4 is an enlarged sectional detail, to which reference will hereinafter be made.

In the drawings, A is the head of the machine.

a is a shaft supported by the head A, having the pulley a', carrying at one end a right shank-edge trimmer, B, and at its opposite end the left shank-edge trimmer, B'.

35 c is a shaft, also supported by the head A, having a pulley, c', arranged to extend at each end beyond the fronts a² a³ of the head A, and carrying at one end the sole-edge trimmer C, set as a right trimmer, and at the other end a sole-edge trimmer C', set as a left trimmer.

The shank and sole-edge trimmers represented are of the duplex variety, and each sole-edge trimmer is covered in part by a hood, D, which is movable toward and from it upon the 45 shaft c. It is formed upon the end of the long sleeve d, and this sleeve has a bracket, d', which extends upward and is secured to the end of the rod d', (see Fig. 4,) so that the sleeve d is prevented from being rotated on the shaft 50 c. The bracket d' also supports the oil-cup d',

and there is formed in the bracket a channel or passage, d', from the cup to the bearing on the shaft c. The sleeve and the bracket are movable horizontally upon the shaft c and rod d', respectively, and a spring, d⁵, surrounding the shaft c, bears against the shoulder d⁶ thereon and against the end d' of the sleeve, and acts in opposition to any movement communicated or given the hood D away or back from the cutter which it covers, such a movement, 60 for instance, as is given by the work for the purpose of uncovering or exposing a section of the cutter.

There is supported by the sleeve d and bracket d', by means of the downward-extending 65 arm e and the lower section or portion, e', of the hood D, which has a hole, e², the sole-edge rest E. The hood D has a hole, e¹, through which the rest E extends, and the arm e also has a hole, e³, for receiving the inner end of the rest. 70 This rest is located below the trimmer and a little in advance of a vertical line drawn through its center, (see Fig. 3,) and it serves as a support upon which the edge of the sole is steadied and rested while the heel end 75 thereof, or a spring-heel, is being presented to the trimmer. It is used, as a rule, only during the trimming of this part of the boot or shoe; but of course I do not confine myself to such use. It is made horizontally movable 80 and horizontally adjustable in its supports, in order that it may be moved entirely back from the face e⁴ of the hood D, and also so that its extent from the face e⁴ may be varied. Both the horizontal movement and the adjustment 85 are obtained by providing the rod E with a screw-thread, e⁵, and by the nuts e⁶ e⁷, which fit the screw-threaded section of the rod and are adapted to be turned thereon against the arm e to lock the rest in place. When the rest 90 is moved back and out of the way, it allows the surface e⁸ of the hood D to be used as a finger-rest, as described in my Patent No. 357,743.

Having thus fully described my invention, I claim and desire to secure by Letters Patent of 95 the United States—

1. The combination, in a sole-edge-trimming machine, of a rotary sole-edge trimmer, and a sole-edge rest, E, arranged in relation to said trimmer to act as a support or rest for the edge 100

of the outsole, and adapted for use in the trimming of the heel end of outsoles and spring heels, as and for the purposes described.

2. The combination, in a sole-edge-trimming machine, of a rotary trimmer, the horizontally-movable hood or piece D, and a sole-edge rest, E, extending horizontally outward from the face e^4 of said hood or piece D, as and for the purposes described.

3. The combination, in a heel-trimming machine, of a rotary sole-edge trimmer, the sole-edge rest E, and means, substantially as specified, for moving the same into and out of operative position, substantially as described.

4. The combination, in a sole-edge-trimming machine, of a rotary trimmer, the hood or piece D, formed upon the end of a sleeve, d,

which is movable upon the shaft carrying the rotary trimmer in opposition to a spring, the bracket d' , the rod d'' , and the arm e, having a hole, e^3 , the hood or piece D, having a hole, e^2 , and the sole-edge rest E, extending through said holes e^3 e^2 to beyond the face e^4 of the hood or piece D, as and for the purposes described.

5. The combination of a rotary trimmer, the hood or piece D, having the hole e^3 , the arm e, having the hole e^4 , and the rest E, having a screw-threaded section, e^5 , and nuts e^6 e^7 , substantially as described.

CHARLES H. TRASK.

In presence of—

F. F. RAYMOND, 2d,
J. M. DOLAN.
